(57) **CLAIM**

The ornamental design for an automobile tire, as shown and described.

DESCRIPTION

FIG. 1 is a front view of the automobile tire of the invention; FIG. 2 is a rear view thereof;

FIG. 3 is a left-side view thereof;

FIG. 4 is a right-side view thereof;

FIG. 5 is a perspective view thereof; and,

FIG. 6 is an enlargement of a portion of the front view thereof.

The broken line showing of the tire sidewall and inner bead and the peripheral boundary between the tire tread and sidewall is for illustrative purposes only and forms no part of the claimed design.
